UNITED STATES PATENT OFFICE.

THOMAS BRENNAN, OF RACINE, WISCONSIN, ASSIGNOR TO J. I. CASE THRESHING MACHINE COMPANY, OF RACINE, WISCONSIN, A CORPORATION.

SEEDING MACHINE.

Application filed February 1, 1928. Serial No. 251,212.

My invention relates to improvements in seeding machines, and particularly to the seed dispensing device known as a double-run feed, which is commonly used in connection with 5 the hoppers of such machines, my object being to provide a simple and effective damper or shield for the passages at either side of the device to cut off the admission of seed thereto, with means for detachably securing such 10 damper in position, my improved damper or cut-off being interchangeable so that it may be readily applied to either passage, as will hereinafter more fully appear.

In the accompanying drawing, forming 15 part hereof, Figure 1 is a sectional view through the hopper showing that side of the dispensing wheel designed to discharge seeds of a large size; Fig. 2, a similar view showing the opposite side of the wheel utilized for distributing smaller seeds; Fig. 3, a detail view 20 showing a portion of the hopper equipped with my improvements; Fig. 4, a side elevation showing the complete dispensing device; and Fig. 5 is a perspective view of the damper 25 which I employ.

In said drawing, the numeral, 5, indicates a seeding machine hopper of any ordinary construction, to the under side of which the dispensing devices, 6, are secured by screws, 30 7, or otherwise, in a well known manner. The dispensing device 6 is of common construction comprising housing members, 8, 9, having a feed-wheel, 10, therein comprising a web 11, provided with outwardly extending flanges, 12, 13, and a hub, 14, by which it is mounted on a driving shaft, 15, in a well known manner, it being the practice to install a series of such dispensing devices in a seeding machine hopper to be operated simultaneously by the 40 shaft 15. The flange 13 of the wheel 10 is of smaller diameter than flange 12, and consequently the seed passage between that side of the wheel and housing member 9 is smaller than the opposite passage formed by the 45 flange 12 and housing 8. The upper portion of wheel 10 is protected by a guard or partition 10' as is common. However, as all of the parts thus far described are common and well known in the seeding machine art they 50 will be referred to hereinafter but incidentally in describing my improvement.

As stated, a number of the dispensing devices 6 are installed in the hopper 5, the bottom of the hopper being spaced, as at 18, between each pair of dispensing devices, which

spaces are covered by a roof-like plate or deflector, 20, the sides, 21, of which may be upturned and secured to the hopper or the plates may be otherwise connected thereto. It will be understood that the grain flows into the 60 passages, as 22, at each side of the dispensing device 6, and, when grain is being distributed of a character to flow through the larger passage of the device, the opposite or smaller passage is covered to prevent grain from 65 entering thereto, and this I accomplish by inserting a damper 25 in the smaller entrance. This damper (Fig. 5) is provided with a floor, 26, and wall, 27 preferably embodying a grip, 28, by which the damper may be readily 70 placed in or removed from the entrance to the passage, the wall, 27, being curved as shown to fit the contour of the guard 10' and thus completely enclose the passage. The damper may also be provided with stops 29 adapted to 75 lie against a housing member to insure that it will be properly maintained in position when inserted. When the damper is thus installed it may be secured in position by any suitable means, that disclosed being a spring 80 latch, 30, pivotally connected to the plate 20 and which may be conveniently turned so that its end will engage a slot, 31, in the damper. It will be observed that each end of said deflector 20 is provided with a latch 30 so that 85 the damper at either side of the dispensing device may be secured, it being necessary according to the character of the seed to be sown to close the larger or smaller passage as required. It will thus be seen that the damper 90 is interchangeable and may be readily applied and secured to either side of the dispensing device, and if for any reason it may be desired to close both passages in some of the devices 95 dampers of the character disclosed, being of uniform size and design, can be employed interchangeably. I am aware that hinged plates or shields and the like have been employed for the purpose explained, but my improved damper requires no permanent connection and may be transferred from one to 100 the other passage, being adapted to be readily secured to and removed from any of the dispensing devices in the hopper as may be desired; and, therefore, what I claim is:

1. In a seeding machine, a dispensing device embodying a housing, a feed-wheel in the housing and spaced therefrom to provide seed passages in each side of the device, and a damper embodying a floor and a wall inserti- 105

- ble over the passages in the housing to prevent the entrance of material into a seed passage.
2. In a seeding machine, a dispensing device embodying a housing, a feed-wheel in the housing and spaced therefrom to provide seed passages in each side of the device, a damper embodying a floor and a wall adapted to be inserted above a seed passage to prevent the entrance of material thereinto, and means for detachably securing the damper in position.
3. In a seeding machine, a hopper, seed dispensing devices in the hopper and spaced from each other, a deflector between the dispensing devices embodying two members inclined downwardly in opposite directions and each member communicating with a dispensing device for directing material into the latter; dampers insertible in the devices for preventing the entrance of seed thereinto, and means associated with the deflector for securing the dampers in the devices.
4. In a seeding machine, a seed dispensing device, and a damper for the device comprising a floor portion, a wall extending from the floor and curved at its upper side, and means on the damper for grasping the same to be inserted and removed from the dispensing device.
- 15 In testimony whereof I affix my signature.

THOMAS BRENNAN.
